SHIELDED PROTECTOR TUBE

Otto Ackermann, Irwin, Pa., assignor to Westinghouse Electric & Manufacturing Company, East Pittsburgh, Pa., a corporation of Pennsylvania

Application April 29, 1939, Serial No. 270,814

3 Claims. (Cl. 175—30)

My invention relates to shielded expulsion discharge-tubes such as are utilized for protecting electrical apparatus against excessive voltages, and more particularly my invention relates to such a tube having arc-responsive gas evolving material therein for assisting in extinguishing the discharge-arc.

An object of my invention is to provide such a protector-tube having two electrodes which extend into the opposite ends of an insulating tube in contact with the bore thereof, said tube being provided with an external shield which is insulated from both electrodes, whereby an optimum operating performance will be obtained, as will be hereinafter described.

A further object of my invention is to utilize a shield consisting of a coating of aluminum paint which is sprayed onto the outer surface of the insulating tube; or the shield may be some other equivalent shielding-means consisting of a plurality of layers of a plurality of overlapping flat conducting flakes or bodies which overlap sufficiently to produce a practically continuous capacitor-effect, while being insulated from each other sufficiently to make the shield incapable of conducting current from end to end thereof under the voltage stress imposed by the normal line-voltage, and probably also under the discharge-conditions of the device.

With the foregoing and other objects in view, my invention consists in the structures, elements, combinations and relative dispositions of parts as hereinafter described and claimed, and illustrated in the accompanying drawing, wherein—

Figure 1 is a sectional view of a simple shielded tube utilizing my invention,

Fig. 2 is an enlarged diagrammatic view illustrative of the functional operation of the shield, and

Fig. 3 is a sectional view of a more elaborate tube embodying my invention.

In Figure 1, my invention is applied to a protector-tube comprising an insulating tube 1 of fibre or other arc-responsive gas-evolving material which has the property of evolving a large quantity of substantially non-ionized gas, or equivalent small-particulate matter, in the presence of an arc. The tube shown in Fig. 1 is symmetrical, both ends being alike, and both ends being furnished with metal electrodes each consisting of an outer ferrule 2 and an inner tubular portion 3 which projects into the insulating tube 1. In accordance with my invention, the tube of Fig. 1 is provided with an outer shield 4 in the form of a coating of aluminum paint

which is sprayed onto the central portion of the outer surface of the tube, so as to form a closely adhering cylindrical sleeve, the ends of which are spaced from both of the outer ferrules 2 of the terminal electrodes.

The essential or most important feature of the aluminum-paint shield is illustrated in Fig. 2, which diagrammatically represents an enlargement of a portion of the shield, showing it to consist of a plurality of layers of overlapping and unconnected metal or conducting flakes 5, the overlapping ends of which are close enough together to have a very strong capacitor-effect between the overlapping flakes, so that the shield 15 operates, electrostatically, very much as if it were a continuous conducting member, whereas, from a conducting standpoint, the separate overlapping flakes or conducting elements are sufficiently well insulated from each other, in general, 20 so that the shield is incapable of actually conducting current from end to end thereof. In other words, when a low voltage is applied to the shield, from end to end thereof, or even when a fairly high surge-voltage is applied thereto, no 25 current is conducted from end to end of the tube, the only current obtained being of practically the same order as the current which is obtained when voltage is applied to an insulator. This insulating property of the shield is extremely useful in increasing the ability of the tube to avoid 30 external current-leakage or flashover.

My shielded tube, in common with all other successful internal-discharge tubes, must have an external flashover-voltage which is higher than 35 the internal flashover-voltage, so that a flashover or arc always occurs on the inside, where it may readily be extinguished. In many designs, notably tubes which are not utilized in conjunction with an external series gap device, it is quite 40 desirable for the external creepage-distance, along the surface of the insulation, or from the outer ferrule 2 of one electrode to the outer ferrule 2 of the other electrode, in Fig. 1, to be greater than the internal discharge-spacing between 45 the inwardly projecting portions 3 of the respective electrodes. In order to afford an adequate factor of safety, I prefer, in such designs, to cause the shield 4 to be separated from both of the electrode-ferrules 2 by creepage-distances, 50 the sum of which is greater than the spacing separating the electrodes 3 within the bore of the tube.

An important feature of my invention is that the terminal electrodes 3, which extend into the respective ends of the insulating tube 1, termi-

nate at a point or points in contact with the bore 6 of the tube, as indicated at 7 in Fig. 1. This feature has a double advantage in that it brings the tip of the electrode, at 7, as close as possible to the adjacent end of the shield 4, since both the shield and the electrode are in contact with the respective walls of the insulating tube 1. In addition to this advantage, the fact that the inwardly projecting electrode 3 terminates in contact with the inner surface of the insulating tube 1 (and it is sufficient if this contact is a very light contact, not necessarily anything approaching a perfect contact), contributes materially to the electrical performance of the tube, by reducing the internal breakdown-voltage thereof, because so-called "surface" discharges start more easily, as at the contacting surfaces at 7, than discharges which must pass through a free air space.

In general, the length of my shield 4, as measured along the length of the tube, is less than the internal arcing-distance or separation between the inwardly projecting terminal-electrodes 3. This feature, again, has several advantages, because, after the shield has been lengthened so as to extend as far, on the outside of the tube, as the internal arcing-distance on the inside, any further extension of the shield, so as to overlap a portion of the inwardly projecting electrode at either end, will have little or no advantage from the standpoint of reducing the internal flashover-voltage, while it will have a very distinct disadvantage in increasing the danger of obtaining an external flashover rather than an internal flashover, that is, an external flashover at a breakdown-voltage which is lower than the internal breakdown-voltage. And aside from the external flashover-voltage, it is extremely desirable to keep down the external surface-creepage or leakage distance, as previously explained.

The operative effect of my shield is to cause practically all of the applied voltage, prior to a breakdown or internal flashover of the tube, to be concentrated in the short spaces, measured through the walls of the tube, between the respective ends 7 of the electrodes and the adjacent ends of the shield 4, so that the voltage-gradient, or stress per centimeter, which appears on the arcing-tips 7 of the electrodes, is much greater than it would have been if the shield 4 had been omitted from the tube.

Fig. 3 shows a more elaborate form of embodiment of my invention, in which the fibre tube 1 is made in the form of a plurality of layers 8, 9 and 10 of telescoping fibre or other insulating tubes of various lengths. The upper electrode in Fig. 3 is in the form of a hollow metal shell 12, which is inserted in the upper end of the outer insulating tube 3, and which terminates in an arcing-tip 13 which is flush with the inner surface or bore of the inner insulating tube or spacer 10. The upper electrode 12 is connected, by means of a threaded steel stud 14, to an upper terminal-member 15 which is connected to a line-conductor 16. The bottom electrode in Fig. 3 is a massive metal casting 17, which has a tubular portion 18 projecting up into the insulating tube and similarly terminating flush with the inner bore thereof. The bottom portion of the lower electrode 7 is also provided with a lateral vent or opening 19 which communicates with the bore of the tubular electrode-portion 18, so as to provide a means for venting the tube. The bottom electrode 17 is also provided with a terminal-member 21 which engages a ground-con-

ductor 22. The outer insulating layer 8 of the insulating tube 1 is provided with a shield 4 similar to that which has been described in connection with Fig. 1.

5 The particular tube which is illustrated in Fig. 3 has a more elaborate internal structure and a more elaborate external structure than the simple tube which is shown in Fig. 1. The internal structure consists of a plurality of slotted 10 "diffuser" elements or plugs 24, 25 and 26, which are spaced by the inner spacers or layers 10 of the composite insulating-tube structure, these so-called diffuser plugs 24, 25 and 26 being built up of pieces of fibre which are slotted, as indicated by dotted lines 28, so as to provide a plurality of arc-discharge paths which are in very close or intimate contact with the walls of the gas-evolving fibre, as described and claimed more explicitly in a patent of Hodnette et al., No. 2,147,440, granted February 14, 1939, and assigned to the Westinghouse Electric & Manufacturing Company.

An external porcelain housing-member 30 is also provided, for the tube which is shown in Fig. 3, said porcelain housing-member being provided with a supporting-clamp 31 which terminates in a supporting-bracket 32, so that the shield 14 is well insulated from the supporting bracket 32, and the entire tubular member 1 is well protected against the weather.

The operation of the tube shown in Fig. 3 is very similar to that which has been described in connection with Fig. 1.

In both of the embodiments of my invention, 35 shown in Figs. 1 and 3, respectively, the entire outer surface of the insulating tube 1, after the shielding coating 4 has been applied, is usually covered with a protective coating of an insulating paint, which covers both the shield and the 40 tube, and which further serves to insulantly protect the shield, while at the same time improving the physical appearance of the device. This outer paint-coating is too thin to be shown on the drawing, other than as the outer surface-line which is indicated at 34. In fact, the aluminum-paint coating 4, which constitutes the 45 shield, is also too thin to be properly shown on the drawing, its thickness being grossly exaggerated for the sake of illustration.

50 While I have illustrated my shield as consisting of a sprayed-on coat of aluminum-paint, I intend that this showing, and in particular the enlarged illustration in Fig. 2, shall be regarded as being symbolic or representative of any substantially functionally equivalent shielding-member which may consist either of small metallic flakes, as in metal paints, or of overlapping larger shielding-elements of much larger overlapping and insulated conducting flakes, sheets or pieces, or other means for causing the shield to have a capacitor-effect substantially as if it were a solid conducting sheet, whereas it is actually incapable of conducting current from end to end thereof.

65 I desire my illustrations of my invention to be construed as being merely illustrations and as not indicating that my invention is specifically limited to any precise structural combination other than is necessarily inferred from the language of the appended claims, when read in the light of the prior art.

I claim as my invention:

70 1. A shielded expulsion discharge tube comprising a tubular insulating housing-structure, two terminal electrodes at the opposite ends of

the tube, respectively, at least one of said electrodes projecting into its end of said tubular insulating housing-structure and terminating at a point or points in contact with the bore of said tubular insulating housing-structure, at least one of said electrodes being vented to the outside of the tube, the internal discharge-space or spaces between the two electrodes within the bore of the tubular insulating housing-structure including arc-responsive gas-evolving insulating material, a shield in contact with the outside surface of said tubular insulating housing-structure, said shield comprising a plurality of layers of a plurality of overlapping flat conducting bodies which are sufficiently well insulated from each other to make the shield incapable of conducting current from end to end thereof, said shield being disposed in non-overlapping relation with respect to both of the electrodes and extending from a point near the arcing-tip of one electrode to a point near the arcing-tip of the other electrode, the extent of the projection of the respective electrode or electrodes into the tubular insulating housing-structure being sufficiently great so that the shield is insulatedly separated from both of said electrodes, externally of the tube, by creepage-distances the sum of which is greater than the effective spacing separating the arcing-tips of the electrodes within the bore of the tubular insulating housing-structure, and means for so supporting the tube that said shield is electrically insulated from ground.

2. A shielded expulsion discharge tube comprising a tubular insulating housing-structure, two terminal electrodes at the opposite ends of the tube, respectively, at least one of said electrodes projecting into its end of said tubular insulating housing-structure and terminating at a point or points in contact with the bore of said tubular insulating housing-structure, at least one of said electrodes being vented to the outside of the tube, the internal discharge-space or spaces between the two electrodes within the bore of the tubular insulating housing-structure including arc-responsive gas-evolving insulating material, a shield in contact with the outside surface of said tubular insulating housing-structure, said shield comprising a composite sheet of a plurality of materials of such nature and composition that the shield has a capacitor-effect substantially as if it were a solid conducting sheet, whereas it is actually incapable of conducting current from end to end thereof, said shield

being disposed in non-overlapping relation with respect to both of the electrodes and extending from a point near the arcing-tip of one electrode to a point near the arcing-tip of the other electrode, the extent of the projection of the respective electrode or electrodes into the tubular insulating housing-structure being sufficiently great so that the shield is insulatedly separated from both of said electrodes, externally of the tube, by creepage-distances the sum of which is greater than the effective spacing separating the arcing-tips of the electrodes within the bore of the tubular insulating housing-structure, and means for so supporting the tube that said shield is electrically insulated from ground.

3. A shielded expulsion discharge tube comprising a tubular insulating housing-structure, two terminal electrodes at the opposite ends of the tube, respectively, at least one of said electrodes projecting into its end of said tubular insulating housing-structure and terminating at a point or points in contact with the bore of said tubular insulating housing-structure, at least one of said electrodes being vented to the outside of the tube, the internal discharge-space or spaces between the two electrodes within the bore of the tubular insulating housing-structure including arc-responsive gas-evolving insulating material, a shield in contact with the outside surface of said tubular insulating housing-structure, said shield comprising a coating of paint comprising a large number of metal flakes arranged in at least partially overlapping layers, with the flakes sufficiently well insulated from each other to make the shield incapable of conducting current from end to end thereof, said shield being disposed in non-overlapping relation with respect to both of the electrodes and extending from a point near the arcing-tip of one electrode to a point near the arcing-tip of the other electrode, the extent of the projection of the respective electrode or electrodes into the tubular insulating housing-structure being sufficiently great so that the shield is insulatedly separated from both of said electrodes, externally of the tube, by creepage-distances the sum of which is greater than the effective spacing separating the arcing-tips of the electrodes within the bore of the tubular insulating housing-structure, and means for so supporting the tube that said shield is electrically insulated from ground.

OTTO ACKERMANN.
